COMBINATION UNITARY WATER SOFTENER
AND SPRAY HEAD HOSE ATTACHMENT

John J. Wagler, Western Springs, Ill.

Application March 9, 1955, Serial No. 34,965

Term of patent 14 years

(Cl. D91—1)

Fig. 1.

Fig. 2.

Fig. 3.

Fig. 1 is a front perspective view of a combination unitary water softener and spray head hose attachment embodying my new design;

Fig. 2 is a side elevational view thereof; and
Fig. 3 is a rear end view thereof.

I claim:

The ornamental design for a combination unitary water softener and spray head hose attachment, substantially as shown.
